C. W. BORG.
TONGUE SHAPING MACHINE.
APPLICATION FILED SEPT. 20, 1906.

909,530.

Patented Jan. 12, 1909.

UNITED STATES PATENT OFFICE.

CHARLES W. BORG, OF ROCK ISLAND, ILLINOIS.

TONGUE-SHAPING MACHINE.

No. 909,530.

Specification of Letters Patent.

Patented Jan. 12, 1909.

Application filed September 20, 1906. Serial No. 335,495.

To all whom it may concern:

Be it known that I, CHARLES W. BORG, a citizen of the United States, residing at Rock Island, in the county of Rock Island 5 and State of Illinois, have invented certain new and useful Improvements in Tongue-Shaping Machines, of which the following is a specification, reference being had therein to the accompanying drawing.

10 My invention relates to improvements in the tongue shaping machine for which Letters Patent were granted to me on the 13th day of September, 1904, No. 769,980, and the object of the present improvement is to 15 reduce the friction between the supporting table and the moving blank or work-piece, which friction may become excessive when the blank is warped or sprung and it becomes necessary to apply heavy pressure to bring 20 it into contact with the work-table. This and other advantages are secured by the construction shown in the accompanying drawings, in which—

Figure 1 is a side view of the machine of 25 the patent above referred to, showing the application of my improvements thereto; Fig. 2 is a side elevation, partially in section of the improved feed mechanism; Fig. 3 is a plan of the same; Fig. 4 is a section on 30 the line IV—IV of Fig. 3 showing one of the feed bars and supporting means therefor, and Fig. 5 is a plan view, on a reduced scale, of the laterally-movable side-dressing cutter-heads and the controlling means therefor.

35 1 represents the main frame of the machine, 2 the feed table extension thereof, 3 the primary feed-apron or movable table of my present improvement, 4 the secondary feed-apron, 5 an intermediate stationary 40 table section, hereinafter referred to, 6 the timed feed chain corresponding to the feed-chain 4 of said Patent No. 769,980, above mentioned, and hereinafter more fully described, 7 the main driving shaft for the feed 45 mechanism, 8 a sprocket wheel on shaft 7, said wheel being connected to a sprocket wheel 9, of the same diameter and number of teeth, by a sprocket chain 10. The wheel 9 is mounted on the driving shaft 11 of the 50 secondary feed-apron mechanism 4, so that both primary and secondary aprons travel at the same lineal speed; as will be readily understood.

55 12, 13 are the driven shafts of the primary and secondary aprons, respectively.

Each of the shafts 7, 11, 12 and 13 carry

paired sprocket wheels 14, 15, 16 and 17, respectively, which wheels carry and propel the chains 18, 19 to which chains are secured the movable feed bars 20, 21, which constitute the feed-aprons, or the feed bars themselves may constitute links of the chain. Each of said feed bars is provided with an intermediate recess 22, adapted to form a chain seat for the feed-chain 6, as will be 65 more fully described hereafter.

In each of the chain-seats of the feed-bars 20 is formed or secured a sprocket tooth 23, adapted to operatively engage spaces between the links of the feed-chain 6, to drive 70 the same synchronously with the movement of the feed-bars 20. The feed chain 6 is, as in the original patent mentioned, provided at suitable intervals with work-driving and centering spurs 24, and also with a suitable 75 number (say three) feed-teeth 25; said feed teeth being so located and "timed" with respect to the cutter actuating cams 26 as to feed the blanks or work-pieces at the proper intervals to be profiled as desired; all as 80 fully described in the beforementioned patent. The side-dressing cutters *c*, *c*, are carried by frames *f*, *f*, each pivoted as at *p* and each controlled by a link *l* carrying a roll-holding collar *t* upon which is mounted 85 a roll *r* bearing upon the controlling-cam 26, as clearly shown in Fig. 5 and in my prior patent.

To assist the spurs 24 in their centering and driving action, the feed-bars 20 and 21 90 are preferably diagonally ridged or fluted, as shown at 27 in Figs. 3 and 4, the ridges on opposite sides of the chain seats being oppositely inclined, as illustrated.

It should be noted that the top faces of all 95 the parts supporting the blank during its movement through the machine are in the same horizontal plane, namely, the feed table 2, feed bars 20, 21 and the stationary table-section 5. As in Patent No. 769,980 100 the chain-way in the feed-table is depressed to drop the feed chain and centering spurs 24 sufficiently to bring the spur points on a level with the feed-table face; but, instead of providing said way with upwardly inclined 105 portions, as in the former construction, the chain seats 22 of the feed bars of the present improvement are made of such depth that their bottoms serve to lift and hold up the chain for the purpose of forcing the centering spurs 24 into the blank and retaining them there during the action of the cutters. 110

To rigidly support the feed bars themselves at the proper height to permit them to make the working turn around their supporting shafts without presenting their top corners 5 above the plane of the work-table face, the sprocket wheels 14, 15, 16 and 17 are journaled at the proper points in the main frame, and the frame is, moreover, provided with slide-ways 28, which have a slight 10 downward curve at their ends, as at 29, to facilitate the receiving and discharging of the feed-bars. These slide-ways not only form an unyielding support for the bars at the proper level but they are so located as to 15 prevent movement of the bars in the direction of their length and may be constantly and amply lubricated so as to occasion much less friction than that between the work-piece and the stationary table-top in the 20 former construction.

The intermediate stationary table-section 5 is inserted to permit the action of the side-dressing heads and chamfering heads of the machine, as fully explained in the prior 25 patent, and this section is provided with a chain-way of suitable depth to maintain the feed-chain at a constant level during its feeding action. As the side-dressing and 30 chamfering heads are controlled by the work-piece itself, no holding down roll is necessary at this part of the table, and the sliding friction between the blank and the table is inconsiderable.

The operation of my improvement is as 35 follows: Power being applied to the shaft 7, a blank placed on the feed-table 2 is first slid forward solely by the travel of one of the feed-teeth 25; this sliding feed being sufficient at this point of the travel since, as yet, 40 the blank is subjected to no pressure nor cutting action. As the bottom face of the forward end of the blank leaves table 2, it is supported in the same plane and carried onward by the feed-bars 21 which are continuously "returned" around the sprocket wheels 45 17 and move into the plane of the work-table face, at the same time presenting a depressed way for the feed chain and lifting the links of said chain sufficiently to force the spurs 50 24 into the lower face of the blank, while the upper faces of the links remain slightly below the ridged upper faces of the feed bars. As soon as the forward end of the blank contacts with the feed-bar, it passes 55 beneath the first of the pressure rollers which serve the triple purpose of holding the blank while the feed-chain spurs are forced into it, of straightening the blank horizontally and holding it down upon the apron sufficiently 60 to give the ridged faces of the feed-bars a driving hold upon the blank to positively feed it. After passing beneath the top-dressing knife, the forward end of the blank leaves the apron 4 and slides along the stationary table section 5, being there shaped 65

by the side-dressing and chamfering knives, successively; the feed-chain leaving its seats in the bars 21 and passing through the chain-way 30 of the table 5, but maintaining the lateral guiding control of the spurs 24. This 70 control is an important consideration in shaping blanks too short to retain the side-guiding and feed power of either feed-apron in its transit from one apron to the other.

After passing the table section 5, the forward end of the blank is picked up by the bars 20, the seats 22 and sprocket teeth 23 of which bars thereafter support and propel the feed chain until they recede downwardly around the sprockets 14. Lastly, the blank 80 is depressed and "backed" by the last pair of pressure-rolls while its lower surface is dressed by the cutter located just beyond the end of the apron 3.

While the spurs 24 are primarily relied 85 upon to center and laterally guide the blank, the ridges or flutes 27 are desirable when any considerable side strain is thrown upon the spurs by the tendency of a twisted blank to "lead" heavily one side or the other of the 90 table by reason of the greater friction on that part of the blank which may contact with the stationary table wholly on one side of the feed-chain and spurs; a tendency which is often increased by the pressure of 95 the holding-down rolls. It will be seen that such "lead" will be entirely obviated by the substitution of a forward carry feed for the ordinary slide feed.

What I claim is:—

1. In a wood-working machine, in combination, an endless traveling feed-apron and an endless feed-chain surrounding said apron and traveling at the same lineal speed.
2. In a wood-working machine, in combination, laterally movable cutters, means for controlling said cutters, an endless feed-apron, a feed-chain operatively connected therewith, and means for driving said feed-chain in timed relation to said cutter-controlling means.
3. In a wood-working machine, in combination, an endless traveling feed-apron comprising bars having depressed seats, and a feed-chain located in said seats and adapted to be driven in unison with said feed bars.
4. In a wood-working machine, in combination, an endless traveling feed-apron comprising bars having depressed seats, sprocket-teeth in said seats, and a feed chain 120 constructed and arranged to be driven by said sprocket-teeth.
5. In a wood-working machine, in combination, primary and secondary endless traveling feed-aprons, vertically journaled 125 cutter-heads located between said feed-aprons, and a feed chain surrounding said feed-aprons and traveling in unison therewith.
6. In a wood-working machine, in com- 130

- bination, laterally movable cutters, means for controlling said cutters, a plurality of endless movable feed-aprons, a feed chain operatively connected with said aprons, and 5 means for driving said feed chain in timed relation with said cutter controlling means.
7. In a wood-working machine, in combination, a plurality of endless movable feed-aprons, a stationary table section between 10 said aprons, laterally-movable cutters in operative relation with said table-section, means for controlling said cutters, a feed-operative relation with said table-section, chain operatively connected with said 15 aprons, and means for driving said chain in timed relation to said cutter-controlling means.
8. In a wood-working machine, in combination, cutters constructed and arranged to 20 dress the top, sides and bottom of a blank, primary and secondary endless traveling feed-aprons, and a feed-chain surrounding said aprons and traveling in unison therewith.
- 25 9. In a wood-working machine, in combination, cutters constructed and arranged to dress the top, sides and bottom of a blank, primary and secondary endless, traveling feed-aprons, an interposed stationary table-section, power connections between said 30 aprons for driving the same in unison, and a feed-chain surrounding said aprons and driven in unison therewith.
10. In a wood-working machine, in combination, an endless traveling feed-apron, a 35 feed-chain supported thereon and driving connections between said apron and chain.
11. In a wood-working machine, in combination, an endless, traveling feed-apron having a depressed chain-way, a feed-chain sup- 40
- ported in said chain-way below the working face of said apron, and driving connections between said apron and chain.
12. In a wood-working machine, in combination, an endless, traveling feed apron 45 having a longitudinally-arranged groove in the working face thereof, and a superposed feed-chain working in said groove.
13. In a wood-working machine, an endless, traveling feed-apron having a continuous, depressed chain-way in the working 50 face thereof and sprocket-teeth located in said chain-way.
14. In a wood-working machine, in combination, laterally-movable cutters, and a feed 55 apron traveling between said cutters and having its feeding face diagonally scored at opposite inclinations upon either side of its longitudinal center line to prevent lateral movement of the blank carried thereby.
15. In a wood-working machine, in combination, laterally-movable cutters, means for controlling said cutters, and an endless, traveling feed-apron having its feeding face 60 diagonally scored to prevent lateral motion 65 of the work-piece during the movement of said cutters.
16. In a wood-working machine, an endless, traveling feed-apron comprising feed-bars, ways for supporting and laterally 70 guiding said bars, the working faces of said bars being transversely scored to prevent lateral motion of the work-piece carried thereby.
- In testimony whereof I affix my signature, 75 in presence of two witnesses.
